CAN BODY MAKER

Ed Laxo, Oakland, Calif.

Application June 2, 1950, Serial No. 165,617

5 Claims. (Cl. 113—12)

1

This invention relates to a can body maker. In can body makers, can bodies are provided with oppositely hooked ends and are wrapped about a horn with the hooked ends interlocked. A bumper steel is caused to hammer the hooked ends to form a side seam in the can body.

In can body makers high speed of operation is essential and the seams should be formed with a high degree of perfection. Defective seams result in leakage of the can and rejection of the can bodies.

One present day conventional can body maker employs a bumper steel carried by a cross head which is rotatably mounted on the upper end of a rod. The rod, in turn, is rotatably mounted on a crank shaft. The cross head is guided for vertical movement by means of a slide. Difficulties are encountered with slides employed for this purpose. Thus, acid or flux used for soldering the seams, splashes over the slide, thereby fouling it, causing defective operation and requiring frequent shutdowns for repairs. Furthermore, for a slide to work satisfactorily it must be relatively long. This increases the over-all height of the machine and makes it difficult for an operator to work on the machine. If the machine is intended to form seams on cans of large diameter, the over-all height is so great that it is necessary to employ platforms for the operators.

It is an object of the present invention to provide an improved type of can body maker.

It is a further object of the invention to provide a can body maker having a bumper guide which eliminates the necessity of a slide.

It is a particular object of the invention to provide a can body maker which eliminates the necessity of a slide for guiding the bumper steel and which involves fewer relatively moving parts than heretofore.

Yet another object of the invention is to provide a can body maker which is low in over-all height.

Still another object of the invention is to provide a can body maker which is readily and accurately adjustable to form side seams on can bodies of different diameters.

These and other objects of the invention will be apparent from the ensuing description and the appended claims.

One form which the invention may assume is exemplified in the accompanying drawings and is described in detail hereinafter.

In the drawings:

Figure 1 is a fragmentary end elevation of the machine.

2

Figure 2 is a section taken along the line 2—2 of Figure 1.

Figure 3 is an elevation of the cross head and its guide mechanism, and it illustrates the manner in which the guide mechanism can be adjusted.

Referring now to the drawings, the body maker of my invention is generally designated as 10, and it comprises a stationary frame 11 in which is journaled a crankshaft 12. The crankshaft 12 has the usual cheeks 13 and crankpin 14, and a connecting rod 15 is provided, the lower end of which is rotatably mounted on the crankpin 14, as by means of a split strap 16 and cap screws 17. The tubular upper end 18 of the rod 15 rotatably receives a bumper pin 19 which has eccentric ends 20 for a purpose explained hereinafter.

20 A cross head 21 is provided having a split collar 22, which is clamped by means of cap screws 23 to bushings 24a on the eccentric ends 20 of the bumper pin 19. The cross head 21 is formed with a groove 24 to receive a bumper steel 30, which is clamped in the groove by means of cap screws 31.

25 Caps 32 are clamped to the ends of the bumper pin 19 and to the sides of the cross head 21, as by means of cap screws 33. The cross head 21 is formed with a guide arm 34, the outer end of which is mounted in the manner explained hereinafter and which serves to guide the movement of the bumper steel 30. The bumper steel 30 bumps or hammers the interlocked hooks 36 on a can body 37 which is clamped to a horn 38, thereby forming a seam which is shown at 36a. The can body is automatically clamped to the horn 38, and its hooked ends 36 are automatically interlocked, by any suitable means such as those well-known in the art, e. g., by means of arms 39. An anvil or backup member 40 is also provided, which is operated automatically by any suitable means to provide a backing for the horn at the instant of impact of the bumper steel thereon. These elements, i. e., the arms 39 and anvil 40, form no part of the present invention, and appropriate means for accomplishing their intended operations are well-known in the art.

40 It will be apparent that the bumper steel 30 swings through an arc which is indicated at 41. It is necessary to provide a means for guiding the bumper steel so that it coincides with the hooked ends 36 at the moment of impact. It is also desirable to provide guide means for causing the bumper steel to swing in a vertical plane at the instant of impact. On the other hand, it is some-

times advantageous to hammer the seam more on one side than on the other. It is, therefore, desirable to provide guide means for the bumper steel which is operable, by appropriate adjustment, to guide the bumper steel vertically, or to bias it toward one side or the other. It is also desirable to provide a means for rapidly and accurately adjusting the machine for cans of different diameters.

To achieve these various objects, the cross head 10 guide arm 34, and a mounting assembly 45 therefore, are provided and will now be described in detail.

A vertical shaft or post 46 is provided, which is fixed to the frame of the machine. A split collar 15 47 is clamped to the shaft 46 by means of cap screws 48. It will, therefore, be apparent that, by loosening the screws 48, sliding the collar 47 up or down the post 46 to the desired position and then tightening the screws 48, the mounting 20 assembly 45 can be adjusted to and clamped in any selected vertical position.

The collar 47 is formed with a boss 49 which is bored out at 50 to receive a pivot pin 51. The pin 51 is clamped in the passage 50 by means of a cap screw 52, and a guide arm extension 53 is rotatably mounted on the pin 51. The outer end 25 of the cross head guide arm 34 is formed with an eye 54 to receive a screw 55 which is threaded at 56 into the guide arm extension 53.

It will be apparent that the cross head guide arm 34 and the bumper steel 30 will swing in an arc 41 having as its center the axis of the pivot pin 51. If this axis lies in the same horizontal plane as the seam, it will be apparent that, at the instant of impact with the can body, the bumper steel 30 will be traveling in a vertical plane which is tangent to the arc 41. If, however, it is desired to hammer the seam on side *a*, then the collar 47 will be moved downwardly along the post 46, and if it is desired to hammer the seam more on the side *b*, then the collar will be moved upwardly along the post 46.

Provision is also made, by the means which will now be described, for adjusting the machine for can bodies of different diameters. Assuming that the machine illustrated in the drawings is intended for forming can bodies having a maximum diameter of $4\frac{1}{16}$ inches (which are referred to in the art as "No. 404" cans), the eye or collar 54 on the cross head guide arm 34 will be located adjacent the guide arm extension 53, as illustrated in Figure 1. If, then, it is desired to adjust the machine to form seams on can bodies having a diameter of, say three inches (No. 300 cans), a horn of suitable diameter will be substituted for that illustrated, and a wider bumper steel (i. e. $1\frac{1}{16}$ inches wider), shown in Figure 3, will be used. Also a tubular spacer 56 will be inserted between the guide arm extension 53 and the eye 54. A screw 55 of appropriate length will, of course, be used. The spacer 56 will be of a length equal to the difference in can body diameter; i. e., in the example given, the spacer 56 would be $1\frac{1}{16}$ inches long.

A further adjustment feature of the machine is provided by the eccentric mounting of the cross head 21 on the bumper pin 19. As stated hereinabove, and as shown in Figure 2 of the drawing, the ends 29 of the bumper pin are eccentric. It happens frequently that some slight vertical adjustment of the bumper steel is required, in addition to adjustments of the guide arm mounting assembly 45 on post 46. This slight adjustment may be accomplished by loosening the cap

75 screws 33, turning the bumper pin 19 until the exact adjustment has been made, and then tightening the cap screws.

It will thus be apparent that a can body maker has been provided which avoids the necessity of employing a slide for guiding the cross head and bumper steel, and which avoids the major disadvantages of a slide, such as fouling of the slide and an undesirably great over-all height of the machine. The bumper guide illustrated in the drawings and described above, is simple in construction and operation. It can be readily adjusted to provide an absolute vertical movement of the bumper steel at the moment of impact, or it can be adjusted to cause the bumper steel to hammer the seam more on one side or the other, as desired. Furthermore, the bumper guide can be readily adjusted to accommodate the machine to can bodies of different diameters.

A feature of major significance of my machine is that it does not constrain the bumper steel to vertical movement but allows it to swing in an arc. The disadvantages of slides are, therefore, avoided. Also, my machine has an advantage over parallel links which have also been used heretofore to guide a bumper steel. A difficulty inherent in parallel link guides is, that the bumper is always maintained in a vertical position, but must necessarily shift laterally during movement. This lateral shifting imparts to the bumper a shearing action at the instant of impact with the can body seam, which has a tendency to shear or deform the seam. In my machine a nearly absolute vertical movement, or a calculated, controlled, biased movement, is imparted to the bumper steel at this critical instant.

I claim:

1. A can body side seam forming machine comprising a frame, means for supporting a can body blank with hooked interlocked ends in a predetermined plane, a bumper member, crank means for actuating said bumper member to hammer said ends and form a seam, guide means for said bumper member including a guide arm fixed at one end to the bumper member and a pivotal mounting for the other end of said arm, said pivotal mounting being rotatable about a single axis and also being adjustably fixed to the frame to locate the pivot axis thereof in or on either side of said predetermined plane, and means including a plurality of spacers for fixing the other end of said guide arm to said pivotal mounting for swinging movement about said pivot axis, said spacers being adapted to adjust the machine to can bodies of different diameters.

2. A can body side seam forming machine comprising a frame, a mandrel for supporting can bodies with their hooks interlocked, and a bumper having a working edge for bumping said interlocked hooks to flatten the same and form a side seam; said machine also comprising a guide for said bumper pivotally mounted at one end on said frame for rotation about a single pivot axis which is parallel to the plane of and is located substantially in the plane of said side seam, said bumper being connected to the other end of said guide, said guide constraining the working edge of said bumper to movement in a circular arc having its center on said pivot axis and which passes through said side seam, the tangent to said arc at its point of intersection with the side seam being substantially perpendicular to the plane of the side seam, said machine also comprising driving means for driving the bumper through said arc, said driving means

acting directly on the bumper so as to impose substantially no bending moment on said guide at the instant of seam formation.

3. A can body side seam forming machine comprising a frame, a mandrel for supporting can bodies with their hooks interlocked, and a bumper having a working edge for bumping said interlocked hooks to flatten the same and form a side seam; said machine also comprising a guide for said bumper pivotally mounted at one end on said frame for rotation about a single pivot axis which is parallel to the plane of and is located substantially in the plane of said side seam, said bumper being connected to the other end of said guide, said guide constraining the working edge of said bumper to movement in a circular arc having its center on said pivot axis and which passes through said side seam, the tangent to said arc at its point of intersection with the side seam being substantially perpendicular to the plane of the side seam; said machine also comprising driving means for driving the bumper through said arc, said driving means being in the form of a crank, a crank pin and a rod rotatably connected at one end to said crank pin and rotatably connected at its other end to said bumper, said driving means acting directly on the bumper so as to impose substantially no bending moment on said guide at the instant of seam formation.

4. A can body side seam forming machine comprising a frame, a mandrel for supporting can bodies with their hooks interlocked, a bumper having a working edge for bumping said interlocked hooks to flatten the same and form a side seam, and a crosshead carrying said bumper; said machine also comprising a guide for said bumper pivotally mounted at one end on said frame for rotation about a single pivot axis which is parallel to the plane of and is located substantially in the plane of said side seam, the other end of said guide being fixed to said crosshead, said guide constraining the working edge of said bumper to movement in a circular arc having its center on said pivot axis and which passes through said side seam, the tangent to said arc

5

at its point of intersection with the side seam being substantially perpendicular to the plane of the side seam; said machine also comprising driving means for the bumper in the form of a crank, a crank pin and a rod rotatably connected at one end to said crank pin and rotatably connected at its other end to said crosshead, said driving means acting directly on the bumper so as to impose substantially no bending moment

10 on said guide at the instant of seam formation.

5. A can body side seam forming machine comprising a frame, a mandrel for supporting can bodies with their hooks interlocked, and a bumper for bumping said interlocked hooks to flatten the same and form a side seam; said machine also comprising a guide arm non-rotatably connected at one end to said bumper and a pivot member rotatably mounting the other end of said guide arm for rotation about a pivot axis parallel to the plane of said side seam, said pivot member being adjustably connected to said frame to locate said pivot axis in the plane of and on either side of the plane of said side seam according to the adjustment of such member; said machine also comprising crank means for driving said bumper in the form of a crank, a crank pin, a connecting rod rotatably mounted at one end on said crank pin and rotatably connected at its other end to said bumper, said crank means being separate from and independent of said guide means.

ED LAXO.

at its point of intersection with the side seam being substantially perpendicular to the plane of the side seam; said machine also comprising driving means for the bumper in the form of a crank, a crank pin and a rod rotatably connected at one end to said crank pin and rotatably connected at its other end to said crosshead, said driving means acting directly on the bumper so as to impose substantially no bending moment

15 on said guide at the instant of seam formation.

5. A can body side seam forming machine comprising a frame, a mandrel for supporting can bodies with their hooks interlocked, and a bumper for bumping said interlocked hooks to flatten the same and form a side seam; said machine also comprising a guide arm non-rotatably connected at one end to said bumper and a pivot member rotatably mounting the other end of said guide arm for rotation about a pivot axis parallel to the plane of said side seam, said pivot member being adjustably connected to said frame to locate said pivot axis in the plane of and on either side of the plane of said side seam according to the adjustment of such member; said machine also comprising crank means for driving said bumper in the form of a crank, a crank pin, a connecting rod rotatably mounted at one end on said crank pin and rotatably connected at its other end to said bumper, said crank means being separate from and independent of said guide means.
